(57) **CLAIM**

The ornamental design for a magnetic head slider, as shown and described.

DESCRIPTION

FIG. 1 is a perspective view of the front, bottom and left side of a magnetic head slider showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof; and,

FIG. 8 is a perspective reference view of the usage.

The portions of the article in broken lines are shown for illustrative purposes only and form no part of the claimed design.
